Term of patent 14 years

Int. Cl. D6—01

U.S. Cl. D15—8

FIGURE 1 is a perspective view of the inflatable pad for a seat showing our new design;

FIGURE 2 is a top plan view thereof;

FIGURE 3 is a front elevational view thereof;

FIGURE 4 is a side elevational view thereof;

FIGURE 5 is a side elevational view taken from the side of the pad opposite to the side view shown in FIGURE 4;

FIGURE 6 is a rear elevational view thereof; and

FIGURE 7 is a bottom plan view thereof.

The broken line showing of a seat in FIGURE 1 is merely for illustrative purposes.

We claim:

The ornamental design for an inflatable pad for a seat, substantially as shown and described.
